UNITED STATES PATENT OFFICE.

BERT CARLISLE, OF SANTA ANA, CALIFORNIA.

DESIGN FOR A LAMP.

Application filed March 30, 1922. Serial No. 1,452. Term of patent 3½ years.

To all whom it may concern:

Be it known that I, BERT CARLISLE, a citizen of the United States, residing at Santa Ana, in the county of Orange and State of California, have invented a new, original and ornamental Design for Lamps, of which the following is a specification, reference being had to the accompanying drawing, forming part thereof.

Fig. 1 is a perspective, and Fig. 2 is a vertical cross section, of a lamp, showing my new design.

I claim:

The ornamental design for a lamp, as shown.

BERT CARLISLE.
